UNITED STATES PATENT OFFICE.

JAMES R. RENIFF, OF CHICAGO, ILLINOIS, ASSIGNOR OF ONE-HALF TO
EGBERT H. GOLD, OF CHICAGO, ILLINOIS.

DRAFT-RIGGING.

No. 852,801.

Specification of Letters Patent.

Patented May 7, 1907.

Application filed October 29, 1906. Serial No. 341,059.

To all whom it may concern:

Be it known that I, JAMES R. RENIFF, a citizen of the United States, residing at Chicago, in the county of Cook and State of Illinois, have invented certain new and useful Improvements in Draft-Rigging, of which the following is a specification.

This invention relates to improvements in a friction draft-rigging.

10 The object of this invention is to provide a draft-rigging for cars in which shocks are absorbed by means adapted to frictionally engage each other, said means being auxiliary to and supplementing the action of the 15 springs ordinarily employed in devices of this character.

A further object of my invention is the production of an efficient device of the above outlined class which is of substantial construction, and, at the same time, not expensive to manufacture.

In the drawings accompanying this specification, Figure 1 is a plan view of a draft-rigging embodying my invention. Fig. 2 is 25 a longitudinal section of the same, the section being taken on the line 2—2 of Fig. 1, looking in the direction indicated by the arrows. Fig. 3 is an enlarged cross-sectional view of the same, the section being taken on the line 3—3 of Fig. 2, looking in the direction indicated by the arrows. Fig. 4 is a perspective view of one of the split cylindrical friction-cases employed in the form of device shown in Figs. 1, 2 and 3. Fig. 5 shows a cross section of the same part taken on the line 5—5 of Fig. 4. Fig. 6 shows a longitudinal section of another form of draft-rigging embodying my invention. Fig. 7 shows an enlarged cross section of the same on the line 7—7 of Fig. 6 looking in the direction indicated by the arrows. Fig. 8 shows in perspective the split rectangular friction-cases used in the form of the invention shown in Figs. 6 and 7. Fig. 9 is a longitudinal sectional view of a 45 third form of device embodying my invention. Fig. 10 shows an enlarged cross section of the same on the line 10—10 of Fig. 9. Figs. 11, 12 and 13 are broken sectional views of further modifications of my invention.

50 In the several figures of the drawings 1, 1 are the draft-beams or draft-arms secured to the bottom of the car and adapted to support the draft-rigging.

2 indicates the draw-bar having at its outer

end a coupler-head 3. Bolted or otherwise secured to the draft-arms 1, 1 are brackets or lugs 4, 4 and 5, 5, forming abutments for the followers. Guide-plates 6, 6 are bolted to the under side of the brackets or lugs 4, 4 and 5, 5 and support the parts of the draft-rigging. Similar guide-plates 7, 7 are bolted to the upper sides of the brackets 4, 4 and 5, 5 and, in combination with the guide-plates 6, 6 maintain the follower plates 8 and 9 in position, permitting them to have movement longitudinally of the device or in a line parallel with the length of the car. Secured to the inner end of the draw-bar 2 and extending backwardly around the rear follower plate 8, is a strap or yoke 10. When a pulling strain is exerted upon the draw-bar 2 the strap 10 will move the follower plate 8 forward against the resistance of the springs and other resisting means, and when a thrust or compressive strain is exerted upon the draw-bar 2, the follower plate 9 will be moved backwardly or toward the follower plate 8 against the resistance of these springs and other means.

Between the follower plates 8 and 9 are arranged a pair of split friction-cases, one of these friction-cases being adapted to be thrust within the other. The outer of these cases is split longitudinally into two parts 11, 12, the inner of these cases being similarly longitudinally split into two parts 13, 14. These friction-cases 11, 12 and 13, 14 are, in the form of device shown in Figs. 1, 2, 3, 4 and 5, cylindrical in form. In the form of device shown in Figs. 6, 7 and 8 these friction-cases are given a rectangular form. In the device shown in Figs. 9 and 10 these cases are cylindrical and other forms are shown in Figs. 11, 12 and 13. The outer friction-casing 11, 12 is provided with wing-like extensions 11^a, 12^a, these extensions being carried across the upper and lower sides of the members 11 and 12. The inner friction-casing is made convex at 8^a where the follower plate 8 engages the same. Within the inner friction-casing 13, 14 is a plate 15 having one of its sides slightly concaved and adapted to be thrust into contact with the inner side of the end of the casing 13, 14. The opposite or inner side of this plate 15 is provided with a lip 15^a extending around the edge of the plate 15 and adapted to hold in proper position the buffing-spring 16. The

opposite end of the spring 16 bears against a plate 17 similarly provided with a lip 17^a. The inner surface of the end of the outer friction-case 11, 12, is given a convex form, 5 the plate 17 bearing upon the rounded surface 9^a formed thereby. Within the coils of the spring 16 I preferably place a second spring 18 adapted to add its force to that of the spring 16. This spring 18 is centered 10 within the spring 16 by bosses 15^b and 17^b upon the plates 15 and 17.

When a pulling strain is exerted upon the draw-bar and is transmitted from said draw-bar through the strap or yoke 10 to the rear 15 follower plate 8, the forward movement of this follower plate 8 tends to open or spread the two halves 13 and 14 of the inner friction-case. At the same time the resistance of the follower plate 9, which is, of course, prevented 20 from having forward movement by the brackets 5, 5, tends to close the halves 11 and 12 of the outer friction-case together. The inner case 13, 14 and outer case 11, 12 are thus caused to frictionally engage each other 25 so that the movement of the first-named of these two cases into and toward the outer case 11, 12, is frictionally resisted. This action takes place because of the fact that the follower plate 8 is in contact with the convex rear end of the inner friction-case, engaging the same at a point substantially in line with its center, while, at the same time, the plate 15 engages the inner side of this case at its extreme upper and lower points, 30 the result being that a leverage is exerted upon the parts of this inner case, tending to move the inner ends of the parts 13 and 14 apart. At the same time the plate 17 is thrust into contact with the inner convex 35 surface 9^a of the case 11, 12, while the follower plate 9 engages the outer surface of the same at points above and below the point 9^a, the result being a leverage tending to press the parts 11 and 12 together and into contact with the inner friction case.

When an inward thrust is given to the draw-bar 2 the strap 10 will move away from the follower plate 8, while the pressure of the draw-bar upon the follower plate 9 will cause 50 the latter to move inward or toward the follower plate 8. Whether the follower plate 8 be moved forward by an outward pull or the follower plate 9 be moved backward by an inward thrust of the draw-bar 2, the follower plates are caused to approach each other, and the action of the parts in resisting 55 this movement is the same in either case.

It will be seen that, broadly considered, the opposite and separating parts of the 60 friction cases are bent levers having each a fulcrum point and an end that receives at all times a thrust, this thrust being increased by the movement of the draw-bar in either direction. The opposite ends of these levers are 65 arranged to overlie each other, the force

tending to move the levers about their fulcrums being so applied as to move these ends toward and into closer engagement with each other. At the same time that these parts are pressed into closer mutual contact they 70 are moved bodily past each other. The friction between these parts and the consequent resistance offered to this latter movement becomes greater as the force applied increases, for the reason that the springs 16 75 and 18 exert more and more pressure upon the parts as these springs are compressed.

In the form of the device shown in Figs. 9 and 10 a third split friction case 19, 20 is inserted into the case 11, 12. Within this 80 inner case 19, 20 is a disk 21 against which are seated the springs. The edge of this disk 21 is formed with an incline adapted to engage suitable inclines formed upon the inner sides of the parts 19 and 20. The 85 pressure of the springs 16 and 18 upon the wedge-disk 21 forces the parts 19 and 20 apart and into closer engagement with the parts 13 and 14. Interposed between the point 9^a at which pressure is exerted upon the ends of the levers formed by the parts 11 and 12 and the ends of the parts 19 and 20 is a plate 22. Interposed between this plate and the wedge-disk 21 is a spring 23, adapted to move the wedge-disk 21 back when the 95 pressure of the springs 16 and 18 is partly relieved by the strain being taken off the device.

In Fig. 11 the device is shown in a modified form wherein the friction between the 100 inner and outer friction-cases is increased by increasing the amount of surface in contact. In this form of the device the friction surfaces are of polygonal instead of circular cross-sectional form. In the form shown in 105 Fig. 12 these surfaces are given a wave-line contour, while in the form shown in Fig. 13 openings are provided in which rods 24 are inserted to increase the friction between the parts.

To maintain the yoke 10 in its proper position relatively to the friction-cases I provide a pair of flanges 25 and 26 extending along each side of the outer friction-case and adapted to confine between them the yoke 10 115 so as to permit only lengthwise movement of the yoke relatively to this friction-case. These flanges may be cast integral with the metal of the parts 11 and 12 of the outer friction-case, or may be formed separately 120 and secured in place by bolts 27 as shown in the drawings.

I claim as my invention:—

1. The combination with a draw-bar, of a yoke attached thereto, and a friction rigging 125 arranged within said yoke and comprising a pair of levers arranged to overlap each other, and means providing fulcrums for said levers, all so arranged that the longitudinal movement of said draw-bar will move the 130

overlapping ends of said levers toward and into closer engagement with each other.

2. The combination with a draw-bar of a yoke attached thereto and a friction rigging arranged within said yoke and comprising a pair of levers arranged to overlap each other and means providing yielding fulcrums for said levers all so arranged that the longitudinal movement of said draw-bar will move the overlapping ends of said levers toward and into closer engagement with each other.

3. The combination with a draw-bar of a yoke attached thereto and a friction rigging arranged within said yoke and comprising a pair of levers having ends arranged to overlap each other and other ends subjected to yielding pressure, and means providing fulcrums for said levers all so arranged that the longitudinal movement of said draw-bar will impart greater pressure to the pressure-receiving ends of said levers and thereby move the overlapping ends of said levers into closer engagement with each other.

4. In a draft-rigging, the combination of a pair of followers, abutments for said followers, a pair of split friction-cases disposed between said followers and adapted to telescope one within the other, and means for causing the friction-cases to frictionally engage each other when the followers are caused to approach each other, said means tending to open the inner friction-case and to close the outer friction-case.

5. In a draft-rigging, the combination of a pair of followers, abutments for said followers, a pair of friction-cases disposed between the followers and adapted to telescope one within the other, a spring within said friction-cases tending to expand the inner of said friction-cases and to cause the outer of said friction-cases to contract, and means whereby said spring may be compressed by the longitudinal movement of the draft-rigging and thereby caused to exert a greater force as the followers are caused to approach each other.

6. In a draft-rigging, the combination with a pair of followers and abutments therefor, of a pair of split friction-cases disposed between said followers and adapted to slide one within the other as the followers approach each other, spring means tending to hold said followers apart and to move said followers toward their abutments, and means adapted to cause the inner of said cases to expand and thereby to frictionally engage the outer of said cases as one of the followers is moved toward the other, and simultaneously to cause the outer of said cases to move inwardly.

60 7. In a draft-rigging, the combination with a pair of followers and abutments therefor, of a pair of split friction cases disposed between said followers and adapted to slide one within the other as the followers approach each other, spring means tending to hold

said followers apart and to move said followers toward their abutments, and means interposed between said spring means and the split friction cases tending to cause the outer of said cases to close upon the inner case as one of the followers is caused to move toward the other.

8. In a draft-rigging, the combination of a pair of followers, abutments for said followers, fulcrumed members disposed between said followers and adapted to slide upon each other as the followers approach each other, and spring means located between said followers and adapted to bear upon said fulcrumed members and thereby to cause the same to swing about their fulcrum each toward the other and to frictionally engage each other.

9. In a draft-rigging, the combination with a pair of followers, of a pair of bent levers disposed between said followers and arranged so that an end of one of said levers overlies an end of the other lever, and spring means adapted to rock said levers on their fulcrums into engagement with each other, said spring means being so arranged as to be compressed by the movement of one of the followers toward the other of said followers.

10. In a draft-rigging, the combination with a draw-bar, of a pair of followers adapted to approach each other when the draw-bar is moved longitudinally, a spring disposed between the followers, a pair of fulcrumed bent levers having each an arm adapted to receive the thrust of the spring and another arm tending to approach the corresponding arm of the other lever, and a second pair of bent levers likewise having each an arm adapted to receive the thrust of the spring, the other arms of said second pair of levers tending to move away from each other and into engagement with the approaching arms of said first pair of levers.

11. In a draft-rigging, the combination with a draw-bar, of a follower adjacent the inner end of said draw-bar, a second follower, a yoke secured to the draw-bar and embracing said followers, abutments for said followers, a spring interposed between said followers and adapted to be compressed by the movement of either of said followers toward the other, a pair of levers having each an arm adapted to receive the thrust of the spring and another arm tending to approach the opposed arm of the other lever, and a pair of levers having each an arm adapted to receive the thrust of the spring and another tending to move away from the corresponding arm of the other lever and into engagement with the second-named arms of the other pair of levers.

12. In a draft-rigging, the combination with a draw-bar, of a pair of followers arranged to approach each other when the draw-bar is moved longitudinally, a spring

tending to separate said followers, means adapted to be expanded by said spring and means adapted to be compressed by said spring, said first-named means being arranged to telescope within said last-named means as the followers are caused to approach each other.

13. In a draft-rigging, the combination with a draw-bar, of an inner friction-case, an outer split friction-case comprising rocking devices having members rigidly connected therewith and engaging with the inner case, a spring tending to rock said rocking devices toward each other and so contract the outer friction-case and cause the same to frictionally engage the inner friction-case, and means whereby longitudinal movement of the draw-bar increases the pressure exerted by said spring, and, at the same time, causes relative movement between said friction-cases.

14. In a draft-rigging, the combination

with a draw-bar, of an outer split-friction-case, an inner split friction-case, spring means tending to expand the inner and to contract the outer of said friction-cases, and means whereby longitudinal movement of the draw-bar causes relative movement between said friction-cases and also increases the pressure exerted by said spring. 30

15. Draft-rigging comprising a draw-bar, a pair of friction cases adapted to telescope one within the other, means for connecting said friction cases with the draw-bar, spring means within said friction cases, and means interposed between said spring means and the friction cases whereby through the action of the spring the outer of said cases is caused to close upon the inner of said cases. 35
